UNITED STATES PATENT OFFICE.

CHARLES F. L. KAUFMANN, WALLER L. KAUFMANN, AND CARL H. KAUFMANN, OF SANTA ANA, CALIFORNIA, ASSIGNORS TO CHAS. KAUFMANN & SONS, OF SANTA ANA, CALIFORNIA, A COPARTNERSHIP CONSISTING OF CHARLES F. L. KAUFMANN, WALLER L. KAUFMANN, AND CARL H. KAUFMANN.

LAMP ATTACHMENT.

1,320,395.

Specification of Letters Patent. Patented Nov. 4, 1919.

Application filed November 5, 1917. Serial No. 200,428.

To all whom it may concern:

Be it known that we, CHARLES F. L. KAUFMANN, WALLER L. KAUFMANN, and CARL H. KAUFMANN, all citizens of the 5 United States, residing at Santa Ana, in the county of Orange and State of California, have invented new and useful Improvements in Lamp Attachments, of which the following is a specification.

10 This invention relates to improvements in vehicle lamps of the type known as "spot lights", and resides in the provision of means for coöperation with the universal mountings of such spot lights, whereby the 15 upward vertical movement of a lamp when the latter is in a certain position in its range of lateral movement, is limited, so that when the lamp is in position to cast its rays directly forwardly in front of the vehicle to which it is attached it will not and cannot 20 be tilted or moved vertically upwardly to such extent that its rays will blind or confuse operators of vehicles or pedestrians in the path of the vehicle to which the lamp is 25 attached.

In a great many of the States throughout the country laws have been adopted regulating the focus of spot and head lights for automobiles in order to prevent accidents due to drivers of vehicles and pedestrians 30 becoming blinded and confused by the glare of approaching vehicle head or spot lights; and to this end it is usually necessary to dispose the lamps in such position that their 35 rays will strike the road at a distance of from forty to seventy-five feet in front of the vehicle to which they are attached. It has been found that lights arranged to throw their rays upon the road within these 40 distances do not prove objectionable to other drivers or pedestrians nor glare to any appreciable extent. It is the primary object of this invention to provide a means of the above mentioned character for use in 45 connection with spot lights which, as a rule are universally mounted; such means acting when the spot light is in road-illuminating position to prevent movement of such spot light upwardly past the point that would 50 cause its rays to be projected upon the road a distance farther than determined upon, for example, sixty feet, and in carrying out the invention the means above mentioned is

preferably embodied in the form of a two-piece attachment, such attachment being 55 particularly constructed for use in connection with spot lights of the type illustrated in the accompanying drawings but being applicable to other types of spot lights as well.

A further object of the invention is to 60 provide improvements of the character hereinbefore named which constitutes a lamp attachment of marked simplicity in construction and inexpensiveness, and which 65 may be readily and easily attached for use in connection with spot lights without requiring any change in the construction of the spot light to which it is attached.

The invention further consists in the 70 novel and useful construction, formation, combination, association and interrelation of parts, members and features, all as hereinafter described, shown in the drawing, and finally pointed out in claims.

In the drawing:

Figure 1 is a rear elevation of a spot light showing the invention embodied in this application attached thereto, and further showing a fragmentary portion of the 80 vehicle to which the spot light is attached;

Fig. 2 is a horizontal sectional view taken on the line x^2-x^2 of Fig. 1, showing one of the stop members or lugs in out of the way position in dotted lines;

Fig. 3 is a fragmentary vertical sectional 85 view taken on the line x^3-x^3 of Fig. 1;

Fig. 4 is a side elevation of a spot light showing a part of the bracket or mounting therefor, and the lamp, broken away, and also showing the lamp in adjusted position 90 in dotted lines; and

Fig. 5 is a detail perspective view of one of the stop members.

Referring particularly to the drawing in which like parts are designated by like reference characters throughout the several views, 1 designates as an entirety a lamp of conventional form such as commonly known as spot lights, and 2 a bracket provided for supporting the lamp upon a vehicle, as at 95 A. The lamp 1 is connected with the bracket 2 by the universal mounting or connecting means 3, and our invention is generally designated 4, and operatively associated with the mounting 3.

The casing 5 of the lamp is pro-

vided with a rearward extension 6 located centrally thereof and which serves as a handle and as a means for connecting the electrical conductors, not shown thereto. 5 Depending from the extension 6 is the post or standard 7 which is reduced as at 8 adjacent to its lower end and defines an annular shoulder 9. The reduced portion 8 is mounted for rotation within an upright 10 split sleeve 10, said sleeve having opposed wings 11 through which a thumb screw 12 is extended. By tightening the thumb screw 12 the sleeve 10 will bind upon the reduced portion 8 of the post 7 and hold 15 said post in position. The sleeve 10 is provided intermediate of its ends with an offset portion which is formed into a split sleeve 13 being disposed at right angles to the sleeve 10 and which is rotatably mounted 20 upon the outer end of the bracket 2. The outer end of the bracket 2 is reduced as at 14 and screw-threaded as at 15 so as to receive a nut 16; the nut 16 holding the sleeves 10 and 13 which constitute the body 25 or essential part of the universal joint, in rotatable relation upon the bracket 2. The bracket 2 is secured by fastening elements such as screws 17 to the vehicle A.

Ordinarily a lamp such as hereinbefore 30 described is adjusted so as to cast its rays at the desired point upon the road in front of the vehicle to which it is attached and when so adjusted may be held in such position by tightening the nut 16 and the thumb 35 screw 12. By loosening the thumb screw 12 the lamp may be turned laterally upon its mountings and by correspondingly loosening the nut 16, may be rotated vertically as desired so that said lamp may be moved 40 to throw its rays in any desired direction.

In carrying out our invention, which is generally indicated in the drawing by the reference numeral 4 there is provided, means for limiting the movement of the lamp when 45 it is in road-illuminating position so that it cannot be elevated to such a degree as to throw its light rays at an elevation which would produce a blinding and glaring effect for the drivers of vehicles approaching or 50 in the path of said rays, and to this end there are preferably provided stop-members 18 and 19 mounted respectively upon the post 7 and bracket 2 for the lamp, such members being adjustable upon said post and 55 bracket so that the position of the lamp when in road-illuminating position may be varied as desired, and also being removable. Each of the members 18 and 19 comprises a split ring 20 having opposed offset ends 21 60 and 22 in which is mounted the screw '3 which acts to bind or hold the ring upon its mounting. Each of the rings is provided with an offset portion or lug 24 having flat side and end faces. The member 19 is positioned upon the bracket 2 so that its lug

24 is upright and has its outer end face disposed in and approximately horizontal plane as shown in Figs. 3 and 4 of the drawing, whereas the member 18 is so mounted upon the post 7 that one of the side faces 70 of the lug 24 is adapted for engagement with and to rest upon the end face of the lug of the member 19, and it will therefore be seen that this engagement of said members provides for the limiting action desired to 75 prevent upward movement of the lamp so that its rays will not prove blinding and confusing for the drivers of other vehicles and for pedestrians.

By loosening the screws 23 the members 80 18 and 19 may be turned or adjusted upon their respective mountings as desired, so that the pitch of the lamp or rays of the lamp may be varied. When the member 19 is turned so as to bring the lug rearwardly 85 of its upright position, the lamp may be tilted upwardly to a greater extent than when said lug is in upright position, and when said member 19 is turned so as to bring its lug forwardly of its upright position said 90 lamp will not be permitted upward movement to the extent so permitted when the lug is in upright position. When the member 18 is adjusted, the point in the range of 95 lateral adjustment of the lamp at which the limiting of the upward movement is provided, may be varied. Therefore it will be seen that should it be desired to swing the lamp slightly to one side or the other of the position which is substantially in line 100 with the longitudinal axis of the vehicle, said position being the normal position, and when it is desired to have the upward adjustment or movement of the lamp limited in a position to one side or the other of 105 the normal position of the lamp, this may be effected by turning the member 18 upon its mounting so as to bring the lug 24 thereof into required position for the desired 110 limiting action.

The member 19 is interposed between the bracket shoulder 25 and adjacent end face of the sleeve 13, such end face having engagement with said shoulder 25 in the absence of the member 19. By tightening 115 the nut 16 the sleeve 13 binds upon the member 19 and holds it securely in place, and it will be seen also that member 19 may be readily positioned or removed as desired. The member 18 is held upon the post 7 in 120 engagement with the shoulder 9 on said post, by the sleeve 10, the removal of the post 7 and member 18 being provided for by the loosening of the thumb screw 12 and removal of the sleeve 10.

The operation of the invention will be apparent with reference to the accompanying drawing; the foregoing description and the following subject-matter.

Assuming that the lamp is in the posi- 125

tion shown in Fig. 1 of the drawing, such position being the normal or road-illuminating position, when it is desired to swing the lamp to one side or the other, this may 5 be done by grasping the extension 6 and turning the lamp laterally until the lug 24 of the member 18 moves out of engagement with the lug 24' of the member 19. At this 10 time the lamp is free to be tilted up or down to its full extent, inasmuch as the lugs are out of engagement with one another and the lamp is not directing its rays straight ahead. It will thus be seen that the lamp may be moved into any desired 15 position laterally, upwardly, or downwardly, when it is turned out of road-illuminating position. When the lamp is again brought to road-illuminating position the lug 24 of the member 18 will rest 20 upon and engage the lug 24' of the member 19 and the upward movement of the lamp is thus limited so as to prevent glaring rays from the lamp from confusing the drivers of other vehicles and 25 pedestrians in the path of the vehicle to which the lamp is attached. Therefore it will be seen that the lamp is prevented upward movement past a point which is near, although preferably and usually out of necessity, owing to the mounting of the lamp, 30 below the horizontal, only when such lamp is disposed at a certain point of its range of movement, such point being arrived at when the lamp is in road-illuminating position. 35

With reference to the foregoing description and the accompanying drawing, it will be seen that we have provided an improvement of great value in spot lights for vehicles such as automobiles, and that such improvement will permit of the use of a great number of spot lights which under ordinary conditions and in a great many sections of the country could not be law- 40 fully used.

Having thus disclosed our invention, we claim and desire to secure by Letters Patent:

1. A lamp mounting including a bracket arm, a post arranged at an angle to the 50 bracket arm, rigidly connected sleeves re-

ceiving the bracket arm and post and rotatable upon the respective members, and co-operating stop members carried by the bracket arm and post for limiting the swinging movement of the mounting in one direction. 55

2. A lamp mounting including a bracket arm, a post arranged at an angle to the bracket arm, rigidly connected sleeves receiving the post and bracket arm and rotatable thereon, rings clamped upon the bracket arm and post, and co-operating stop lugs carried by the rings and arranged to engage each other to limit the swinging movement of the mounting in one direction. 65

3. A vehicle lamp, comprising a post to which the lamp is attached, a bracket, a mounting comprising sleeves disposed at right angles to one another, one of said sleeves being rotatable upon the bracket, 70 said post being rotatably mounted in the other of said sleeves, rings mounted upon the post and bracket and held in position by said sleeves, and lugs on said rings adapted to engage one another when the 75 lamp is in one of its various positions so as to prevent upward movement of the lamp.

4. A vehicle lamp, comprising a post to which the lamp is attached, a bracket disposed at right angles to the post, a mounting including integral sleeves having one sleeve rotatably mounted upon said bracket and the other sleeve rotatably receiving said post, split rings mounted upon said post 80 and bracket and held in place by said sleeve, screws for clamping the split rings in position, and lugs upon said split rings adapted to engage one another and to prevent upward movement of the lamp when the latter 90 is in one of its various positions.

In testimony whereof, we have signed our names to this specification in the presence of two subscribing witnesses.
